UNITED STATES PATENT OFFICE.

HARRY C. ODENKIRK, OF CLEVELAND, OHIO.

DESIGN FOR A WASTE-WATER TRAP.

53,747.

Specification for Design.

Patented Aug. 26, 1919.

Application filed March 8, 1917. Serial No. 153,515. Term of patent 14 years.

To all whom it may concern:

Be it known that I, HARRY C. ODENKIRK, a citizen of the United States, residing at Cleveland, in the county of Cuyahoga and State of Ohio, have invented a new, original, and ornamental Design for a Waste-Water Trap, of which the following is a specification, reference being had to the accompanying drawings, forming a part thereof.

In the drawings, Figure 1 is a perspective view of the trap; Figs. 2 and 3 are elevations thereof on opposite ends; Fig. 4 is a plan.

I claim:

The ornamental design for a waste water trap, substantially as shown in the drawings.

HARRY C. ODENKIRK.
